UNITED STATES PATENT OFFICE.

ERNST TOENNIESSEN, OF TUBINGEN, GERMANY.

WHEEL FOR PRESSING THE EMPTY TUBES UPON THE SPINDLES OF SPINNING AND DOUBLING FRAMES.

Application filed January 8, 1927, Serial No. 159,978, and in Germany January 11, 1926.

This invention relates to a wheel for pressing the empty tubes upon the spindles of spinning- and doubling-frames. Up to the present the empty tubes or bobbins were 5 pressed upon their spindles either by hand or mechanically. It is, however, a well known fact that the pressing by hand requires much time. The apparatus of known type have the inconvenience to only press 10 those tubes tightly onto the spindles which snugly fit, consequently only tightly pressing those tubes onto the spindles which are higher situated, whilst the remaining, somewhat lower situated tubes, are not pressed 15 on at all. Accordingly, when the machine is started, the last-mentioned tubes run idle and the yarn does not receive the desired twist. The result is, that the threads break 20 on the spinning frame and also during the further treatment.

The present invention, as will hereinafter be understood, avoids all these inconveniences.

One form of construction of the object of the invention is shown, by way of example, 25 in the accompanying drawing.

Fig. 1 is a front elevation of the improved wheel placed upon the spindles.

Fig. 2 is a cross section on line A—B of Fig. 1.

30 The advantages of the present invention consist therein, that a wheel R, which is provided at its centre with a hand-lever or shaft h, serving to guide and press the wheel over the tubes H, presses all the tubes, 35 one after the other, e. g. each tube separately, always corresponding to their seat, tightly and uniformly onto their spindles. Wheel R is constructed like a wheel of a railway car (Fig. 2), with the difference, however, 40 that instead of the smooth running surface, a circular running surface of rounded-off teeth r (Fig. 1) is provided, the position of said teeth being so accurately calculated, that the intervals between the teeth 45 exactly fit the correct position of the tubes, e. g., the teeth per se always engage the intervals between the tubes.

The operation is as follows:

After having taken off the charged tubes, and after having loosely placed the new 50 empty tubes on the spindles, the workman takes the shaft h in his hands, the teeth of the wheel being directed towards the machine. He starts at one end of the machine, places one interval between two teeth r on the first 55 tube H and then walks along the machine in rolling the wheel over the row of loosely set tubes H. The accurately calculated position of the teeth r will, when said wheel is rolled over the tubes, uniformly and tightly 60 press the tubes upon the spindles, the intervals between the teeth coming in touch with the tubes to be pressed.

Practice has shown that in this manner 500 and more tubes can easily be tightly 65 and uniformly pressed upon their spindles in a few seconds, whereas the same work by hand affords ten times as much time. The 70 advantages of the present invention are to be found in the economy of time and in the good seat of every single tube after the hereinafore-mentioned operation has taken place.

I claim:

1. In a device for pressing empty tubes 75 upon the spindles of spinning- and doubling frames, comprising in combination a wheel with a continuous circular running surface of rounded-off teeth, means fixed at the centre of the wheel for handling the same, the 80 intervals of said teeth being so situated that they accurately fit the several tubes the one after the other when the wheel is rolled over the row of tubes.

2. In a device for pressing empty tubes 85 upon the spindles of spinning- and doubling frames, comprising in combination a wheel with a continuous circular running surface of rounded off teeth, a hand-lever or shaft at the centre of the wheel for handling the 90 same, the intervals of said teeth being so situated that they accurately fit the several tubes the one after the other when the wheel is rolled over the row of tubes.

In testimony whereof I affix my signature.

ERNST TOENNIESSEN.
